SIDNEY W. FARNSWORTH, OF PITTSBURGH, PENNSYLVANIA, ASSIGNOR TO WESTINGHOUSE ELECTRIC AND MANUFACTURING COMPANY, A CORPORATION OF PENNSYLVANIA.

ARC-CONTROLLING MEANS FOR VAPOR-CONVERTERS.

1,275,886.

Specification of Letters Patent. Patented Aug. 13, 1918.

Application filed August 6, 1915. Serial No. 44,001.

To all whom it may concern:

Be it known that I, SIDNEY W. FARNSWORTH, a citizen of the United States, and a resident of Pittsburgh, in the county of Allegheny and State of Pennsylvania, have invented a new and useful Improvement in Arc-Controlling Means for Vapor-Converters, of which the following is a specification.

My invention relates to methods of, and apparatus for, controlling the power arc in a vapor converter, and it has for its object to provide means of the character mentioned that shall maintain said arc in a stable condition upon either the anode or the cathode 15 or upon electrodes of both polarities, if so desired.

In the accompanying drawing, Figure 1 is a side view, partially in section and partially in elevation, of a vacuum-type converter embodying one form of my invention; and Fig. 2 is a top view, partially in plan and partially in section, of a portion of the converter shown in Fig. 1, illustrating more clearly the structure thereof.

In the operation of vacuum-type converters, there is frequently a marked tendency for the power arc to move about in an erratic manner under the influence of obscure forces, such, for example, as thermal influences and unbalanced gas and vapor pressures and conductivities. In the ordinary anode, it is substantially impossible to liberate all the occluded gases in the process of treating-out, said process being effective only in the lower and more exposed portions of the electrode. Any wandering of the arc away from such treated portions to portions more or less charged with occluded gases results in a deterioration of the vacuum and unsuccessful operation. In like manner, the erratic wandering of the lower end of the arc over the surface of the cathode results in uncertain and unstable action, and the insertion of any solid shielding body into the cathode for the purpose of restricting this action may be harmful because the arc may operate in immediate proximity thereto, liberating gases therefrom and producing other undesirable results.

By my invention, I avail myself of the well-known phenomenon of the action of a magnetic field on a current-carrying arc in accordance with Fleming's left-hand motor rule and I so dispose magnetic fields adja-

cent to the electrodes of a vapor converter 55 as to effectually minimize all of the above-described harmful effects. A feature of my invention which is especially worthy of note is that I may obtain the desired magnetic fields by the suitable shaping of the 60 current leads of the converter, under certain conditions even disposing said shaped current leads within the container itself.

Referring to Fig. 1 of the accompanying drawings for a more detailed understanding of my invention, I show the container of a vapor converter at 7, said converter being equipped with a main anode 8 and with a cathode 10, preferably composed of vaporizable reconstructing material, such, for example, as mercury or suitable amalgams. Current is supplied to the anode 8 through an anode lead and stem sealed into the cover of the container 7 in the usual manner. The cathode 10 may be insulated from the container 7 or not, as is desired, but current is supplied thereto through a loop or bight 20, preferably composed of seamless conducting tubing, having its right-hand branch 22 disposed to form an arc-controlling helix 23 80 about the anode 8. Said branch 22 is then coiled in the form of a circular helix 24, disposed slightly above the surface of the cathode, before joining the left-hand branch 25. Contact is made with the material of 85 the cathode 10 in a loop 26 at the foot of the branch 25 so that load current from the cathode flows entirely through the coils 24 and 23 before reaching the cathode lead 28.

In operation, let it be assumed that an arc 90 is initiated between the lower portion of the anode 8 and the central portion of the cathode 10 by any suitable means, such, for example, as a keep-alive circuit 27. The current flowing from the cathode 10 through the 95 solenoids 23 and 24 produces a toroidal-shaped bundle of magnetic flux surrounding the active portions of both the anode and the cathode. Said coils are wound and connected in such manner that, if the arc approaches 100 either of said flux bundles, in attempting to flow from or to an undesired portion of an electrode, there is developed a force, in accordance with Fleming's left-hand motor rule, operating to return said arc to the desired central position. Thus, the arc is effectively prevented from operating upon the upper untreated portions of the anode 8

and from reaching and running up the wall of the container 7 adjacent the surface of the cathode 10.

I have illustrated my invention as embodied in a converter of the well known mercury-vapor type wherein the current flow has the form of an arc, but it is obvious that said invention is susceptible of application to other forms of discharge apparatus, whether operating at atmospheric pressure or at greater or less pressures and whether taking the form of an arc or of other types of current flow between electrodes. While, in certain of the subjoined claims, I have employed the term "arc" in referring to the current flow, I desire it to be understood that said term is not used in a limiting sense but as indicative of, and referring to, any and all forms of current flow between electrodes.

20 While I have shown my invention in its preferred form, it will be obvious to those skilled in the art that it is susceptible of various minor changes and modifications without departing from the spirit thereof, and I desire, therefore, that only such limitations shall be placed thereupon as are imposed by the prior art or are specifically set forth in the appended claims.

I claim as my invention:

- 30 1. The combination with electric apparatus embodying means for producing an arc between two electrodes, of a solenoid bent into the form of a ring and disposed adjacent to one of said electrodes so that said arc traverses said ring, and means for producing current flow through said solenoid having such direction, with respect to the direction of said arc, as to maintain said arc upon a predetermined portion of said electrode.
- 35 2. In a vacuum-type converter, the combination with an anode provided with an arc-emitting surface which has been rendered substantially free from occluded gases, of means for producing an arc from said arc-emitting surface, a solenoid bent to form a toroid and mounted adjacent to said arc-emitting surface, said toroid encircling said arc and having its plane disposed substan-

tially normal thereto, and means for energizing said solenoid, whereby magnetic flux is caused to thread therethrough, said magnetic flux surrounding said arc and determining the zone of impact thereof on said anode.

3. In a vacuum-type converter, the combination with an anode, of a cathode, means for producing an arc therebetween, a winding disposed to produce a toroidal shaped bundle of magnetic flux adjacent to one of said electrodes, the lines of said field individually surrounding said arc, whereby the zone of impact of said arc upon said electrode is defined, and means for energizing said winding by the load current of said converter.

4. In a vacuum-type converter, the combination with an anode, of a cathode, means for producing an arc therebetween, and means for producing a fixed toroidal-shaped bundle of magnetic flux adjacent, and parallel, to the surface of said cathode and surrounding said arc, the lines of said field individually surrounding said arc, whereby the zone of impact of said arc upon said cathode is defined.

5. In a vacuum-type converter, the combination with an anode, of a cathode, means for producing an arc therebetween, a solenoid bent into the form of a torus disposed adjacent and parallel to the surface of said cathode so as to encircle said arc and means for energizing said solenoid by the load current of said converter.

6. In a vacuum-type converter system, the combination with an evacuated container, of an anode, a cathode, current leads thereto, and means for producing current flow in said leads and between said electrodes, a portion of the cathode lead being disposed within said container and being formed into a toroidal-shaped solenoid, adjacent and substantially parallel to the arc-receiving surface of said cathode, whereby the zone of arc-impact of said cathode is defined.

In testimony whereof, I have hereunto subscribed my name this 24th day of July 1915.

SIDNEY W. FARNSWORTH.
